DESIGN FOR A SHOE

Herbert Holtz, Haverhill, Mass.

Application November 15, 1934, Serial No. 54,030

Term of patent 3½ years

To all whom it may concern:

Be it known that I, Herbert Holtz, a citizen of the United States, residing at Haverhill, in the county of Essex and State of Massachusetts, have invented a new, original, and ornamental Design for a Shoe, of which the following is a specification, reference being had to the accompanying drawing, forming part thereof, in which:

Fig. 1 is a top plan view and Fig. 2 is a view in side elevation of a shoe showing my new design.

I claim:

The ornamental design for a shoe as shown.

HERBERT HOLTZ.
